UNITED STATES PATENT OFFICE.

PETER A. CHOTT, OF ST. LOUIS, MISSOURI.

SUSPENDER ATTACHMENT FOR WAISTS OR SHIRTS.

SPECIFICATION forming part of Letters Patent No. 681,102, dated August 20, 1901.

Application filed September 17, 1900. Serial No. 30,210. (No model.)

To all whom it may concern:

Be it known that I, PETER A. CHOTT, a citizen of the United States, residing at the city of St. Louis, in the State of Missouri, have 5 invented certain new and useful Improvements in Suspender Attachments for Waists or Shirts, of which the following is a full, clear, and exact description, reference being had to the accompanying drawings, forming 10 part of this specification.

My invention relates to a waist or shirt having means applied thereto for supporting garments, the device being more particularly intended for men's wear to provide supporting 15 means for pants in connection with shirt-waists.

My invention consists in features of novelty hereinafter fully described, and pointed out in the claim.

Figure I is a view showing a waist with my improvement applied thereto. Fig. II is a detail perspective view of the attachment. Fig. III is a modification of the attachment.

1 designates the waist, provided with a series of apertures 2, extending through the band 3 thereof. The suspender attachments, which may be of any desirable number, though preferably three, are applied to the waist at suitable positions. Each attachment 25 comprises a tape 4, preferably stitched at one end to the waist and provided with a series of apertures 5. The unattached or free end of the tape receives a hook 6, provided with a spring-pin 7, that passes through a 35 loop in the free end of the tape. The tape is looped downwardly and passes loosely through a buckle 8, that carries buttonhole cords or straps 9. The tapes 4 being arranged loosely in the buckles 8, permit of 40 the buckles sliding freely thereon, and the length of the tapes in which the buckles are carried may be readily altered at will by removing the hooks 6 from the apertures 5 in the tape and inserting the hooks in other apertures, thereby increasing or diminishing 45 the lengths of the loops, and consequently the length of the attachment, according to requirements to properly support the garment to which the attachment is applied.

50 The buttonhole cords or straps 9 are designed to pass through the apertures 2 in the waistband and to be connected to the pants or other garment to be supported. It is pref-

erable that there should be sufficient fullness in the waist to permit of its blousing over the 55 apertures 2 and ends of the buttonhole cords or straps, so as to hide such parts from exterior view.

The hooks 7 are connected to the tapes 4 by the spring-pins 7 in order that they may be 60 readily removed from the tapes, after which the buckles and buttonhole cords or straps may be slipped from the tapes over their free ends, and this being done the tapes alone remain attached to the waist, so that it can 65 be readily laundered.

In Fig. III, I have shown a modification in which the tape 4^a is equipped with a buckle 6^a, used in lieu of the hook 6. The buckle 6^a is provided with a yoke 7^a, that receives the 70 free looped end of the tape, which is secured by a button 10. The buckle 8^a and button-hole-strap 9^a are applied to the depending loops of the tape 4^a in the same manner as described in the form of attachment shown in 75 Figs. I and II, and the length of the loop is diminished or increased by moving the buckle 6^a upwardly or downwardly on the tape.

The attachment herein shown and described provides a simple and efficient means 80 for supporting men's pants and places the supporting means within the article of wearing-apparel where they are out of view, thus affording a more sightly appearance to the apparel.

I have shown the device applied to a man's 85 waist; but it is obvious that it may be applied to men's shirts and also that it may be applied to ladies' waists as a support for skirts with equal advantage to its use for men's wear. 90

I claim as my invention—

The combination with a waist or shirt having a series of apertures about the waist-line thereof, of a tape, the upper end of which is secured on the inside of the shirt or waist 95 above the waist-line, a series of apertures in the tape near the upper end of the same and a catch secured to the lower end of the tape adapted to engage said apertures, and the cords 9 which coöperate with the apertures 100 in the shirt or waist.

PETER A. CHOTT.

In presence of—

E. S. KNIGHT,
N. V. ALEXANDER.
